US0D1096699S

(12) **United States Design Patent** (10) **Patent No.:** **US D1,096,699 S**
(45) **Date of Patent:** **** Oct. 7, 2025**

(54) **LOUDSPEAKER**

(71) Applicant: **Samsung Electronics Co., Ltd.**

Suwon-si (KR)

(72) Inventors: **Chulyong Cho**, Suwon-si (KR);
Jaewook Yoo, Suwon-si (KR); **Yonggu Do**, Suwon-si (KR); **Dongwook Kim**, Suwon-si (KR); **Jihae Lim**, Suwon-si (KR)

(73) Assignee: **SAMSUNG ELECTRONICS CO., LTD.**, Gyeonggi-Do (KR)

(**) Term: **15 Years**

(21) Appl. No.: **29/883,189**

(22) Filed: **Jan. 25, 2023**

(30) **Foreign Application Priority Data**

Aug. 16, 2022 (KR) 30-2022-0033016

(57) **CLAIM**

The ornamental design for a loudspeaker, as shown and described.

DESCRIPTION

FIG. 1 is a front perspective view of a loudspeaker, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another perspective view showing an example state of use wherein the front plate of the loudspeaker is separated; and,

FIG. 10 is another rear perspective view showing an example state of use wherein the stand of the loudspeaker is separated.

(Continued)

The broken lines in the figures depict portions of a loudspeaker that form no part of the claimed design.
